UNITED STATES PATENT OFFICE.

LOREN W. RICKY, OF SANTA CRUZ, CALIFORNIA, ASSIGNOR OF ONE-HALF TO WILLIAM O. KERRICK, OF SANTA CRUZ, CALIFORNIA.

SEPARATOR FOR CENTRIFUGAL EXTRACTORS.

Application filed May 6, 1924. Serial No. 711,499.

To all whom it may concern:

Be it known that I, LOREN W. RICKY, a citizen of the United States, and resident of Santa Cruz, in the county of Santa Cruz 5 and State of California, have invented certain new and useful Improvements in Separators for Centrifugal Extractors, of which the following is a specification.

This invention relates particularly to a 10 device for separating different lots or bundles of clothes when placed in an extractor for drying.

It is one object of the invention to provide a separator that can be easily inserted 15 through the opening in the top of the basket of the extractor and yet so constructed as to provide a substantially rigid central portion and a flexible outer portion, the whole having substantially the same diameter as 20 the interior of the basket in which it is to be used.

It is another object of the invention to provide a device of the character indicated that will be economical to manufacture, strong, 25 durable, substantial, and highly efficient in its practical application.

Other objects and advantages will appear in the following description, and in the drawing in which,

30 Figure 1 is a vertical section through a basket with my improved separator in position.

Figure 2 is an enlarged plan view of a portion of the separator.

35 Figure 3 is a sectional view on line 3—3 of Figure 2.

Figure 4 is a sectional view through a portion of another embodiment of the invention.

40 Referring more particularly to the drawing, 1 indicates a circular metallic plate having a substantially smaller diameter than the interior diameter of the basket 2 and a smaller diameter than the opening 3 in the 45 top of the basket.

The plate 1 in the present case has a central opening 4 formed therein, the edge being turned at right angles a distance as at 5, and several smaller openings 6 having 50 their edges 7 turned in the same direction as edges 5 of opening 4.

At 8 is shown an annular flexible element 55 preferably built up of two or more sheets of heavy canvas sewed together as at 9 and provided with openings corresponding to

the openings in plate 1. This element 8 has an outer diameter substantially equal to the inner diameter of basket 2 and is arranged on plate 1 with the several edges 5 and 7 of openings 4 and 6 passing therethrough. 60

At 10 is shown a second plate similar in size to plate 1 and having similar openings therein without the turned edges as indicated at 11 and 12. This plate is arranged on canvas element 8 on the opposite side to plate 1 with the several turned edges 5 and 7 of openings 4 and 6 passing therethrough through openings or orifices 11 and 12.

By turning down edges 5 and 7 into close contact with plate 10 and inserting eyelets 70 through both plates 1 and 10 and the canvas therebetween as shown at 13 the three elements 1, 8 and 10 and securely bound together in one integral whole.

It may now be seen that where the basket 75 2 is provided with a central element 14 one bundle of clothing may be inserted therein as at 15, the separator device dropped into position thereon through opening 3 and then a second bundle of clothing placed 80 therein as at 16. By placing a second separator on top of the second bundle the whole is held securely in position without danger of any portion of one bundle becoming mixed with the other. 85

These central plates 1 and 10 reinforce the separator to such an extent that its life is prolonged over a period of years whereas the rotation at high speed of an unreinforced canvas separator soon tears the canvas apart 90 at the center.

The smaller openings 6 are used for finger 95 holes in placing and removing the separator from the basket, while their clinched edges help to bind the several elements together.

It is obvious of course, that where a basket does not have the central element 14 the plates do not require the central openings 5 and 11, this form of a separator being shown in Figure 4.

While I have herein shown and described the preferred embodiment of the invention, it is to be understood that changes in form and construction may be made within the scope of the appended claims. 105

I claim:

1. A separator for centrifugal extractors comprising an annular element of flexible material having its central portion reinforced with a substantially rigid plate. 110

- 2
2. A separator for centrifugal extractors comprising an annular element of flexible material, and a substantially rigid plate of less diameter than said flexible element arranged on each side of its central portion, the three elements being secured together to form an integral whole.
  3. In combination with the basket of an extractor, having a relatively small entrance opening, of a separator having a flexible

marginal portion and a reinforced central portion, the latter being of less diameter than the entrance opening to the basket.

4. In combination with the basket of an extractor, having a relatively small entrance opening, of a distortable separator insertable through the opening and having a reinforced central portion.

LOREN W. RICKEY.
